UNITED STATES PATENT OFFICE.

FRANK I. STROMENGER, OF VILLA PARK, NEW JERSEY.

RAILWAY APPLIANCE.

1,202,606.

Specification of Letters Patent. Patented Oct. 24, 1916.

Application filed March 1, 1916. Serial No. 81,459.

To all whom it may concern:

Be it known that I, FRANK I. STROMENGER, a citizen of the United States, residing at Villa Park, in the county of Monmouth, State of New Jersey, have invented certain new and useful Improvements in Railway Appliances; and I do hereby declare the following to be a full, clear, and exact description of the invention, such as will enable others skilled in the art to which it appertains to make and use the same.

This invention relates to improvements in railway appliances, and particularly to railway ties and fasteners.

One object of the present invention is to provide a novel device for supporting the rails of a railway, which will take the place of the ordinary wooden ties, and not be subject to any great deterioration.

Another object is to provide a device of this character which is of such simple construction that the whole structure can be quickly and easily set in position to effectively support the rails.

Other objects and advantages will be apparent from the following description when taken in connection with the accompanying drawing.

In the drawing: Figure 1 is a side elevation of my improved rail support and fastening; Fig. 2 is a top plan view; Fig. 3 is a transverse section on the line 3—3 of Fig. 1; Fig. 4 is a horizontal section on the line 4—4 of Fig. 3.

Referring particularly to the accompanying drawing, the support consists of a plurality of superimposed sections 10, 11 and 12, each of which is molded in any suitable manner from concrete and has formed in its upper and lower faces the transverse intersecting grooves 13 for the reception of the binding material which is inserted between the several sections in assembling the supports. Preferably the supports are made in a number of sections, as indicated, for convenience in handling and are removable at the point of use. The binding material may be any suitable mortar in general use,

the filling of the mortar into the grooves 13 properly keying the several sections of 50 the supports together. Formed vertically through all of the sections are openings 14 through which are disposed the vertical bolts 15, the lower ends of the bolts passing through a metal plate 16 on which the bottom section 12 rests. Mounted on the top of the uppermost section is a cap plate 17 which is formed with the depending surrounding flange 18 engaging with the sides of the upper section. Formed through the 60 cap plate are openings 19 which align with the openings of the sections and receive the upper ends of the bolts therethrough. The rail 20 is disposed on the cap plate and is held in place by the clamp plates 21 which 65 are also apertured to receive the upper ends of the bolts. Nuts 22 are engaged on the upper ends of the bolts above the clamp plates and thus hold all of the parts together and the rail on the top thereof. These supports are sunken into the ground in parallel rows so as to properly support and space the rails from each other. The supports may be buried in the ground to any depth desired, and the sections may be increased 70 or decreased as found convenient, so that the rails can be supported at any height above the ground or approximately on a level with the ground.

What is claimed is:—

A rail support, comprising in combination a plurality of concrete sections providing a pedestal, opposing faces of said sections having key grooves formed therein, and successive sections being shaped to provide a constant taper to the pedestal, a base plate, a cap plate and tie rods passing through all of said sections and said base and cap plates.

In testimony whereof I affix my signature 90 in the presence of two witnesses.

FRANK I. STROMENGER.

Witnesses:

JAMES P. VAN SCHOICK,
C. HENRY CRAIG.
